UNITED STATES PATENT OFFICE.

JAMES GOVAN, OF BIRCHCLIFF, ONTARIO, CANADA, AND HAROLD S. ASHENHURST, OF CHICAGO, ILLINOIS, ASSIGNORS, BY MESNE ASSIGNMENTS, TO INSULEX CORPORATION, OF CHICAGO, ILLINOIS, A CORPORATION OF DELAWARE.

BUILDING CONSTRUCTION.

Application filed March 3, 1925. Serial No. 12,914.

Our invention relates to roofs, floors or other horizontal or inclined walls, and particularly to novel means for insulating and reinforcing such walls.

5 It is well known that much of the heat loss in buildings is by radiation through the roof, and an object of our invention is to provide a roof that may be economically constructed, and that will have high insulating efficiency.

A further object is to provide a roof construction that may be made entirely fire-proof by the use of steel structural elements or partly fire-proof by the use of wood 15 rafters. In either case, the roof is composed of cellular material and is suitably reinforced not only for the purpose of carrying the requisite load but to provide against the collapse of the roof in the event of an interior fire. Incidentally, the reinforcing elements are so disposed within the body of cellular material that they are unaffected by an ordinary degree of heat beneath the material.

25 A further object is the provision of a construction that will avoid the necessity for the use of temporary forms. This results in a material saving in the cost of labor and materials.

30 In the construction of the roof of our invention, we utilize the insulating material disclosed in the prior Ashenhurst patent, Reissue No. 15,952 of November 25, 1924, in which is disclosed a material composed 35 mainly of gypsum, together with suitable chemicals that will, in the presence of water, react and evolve a gas, thereby causing the expansion of the mass and finally the setting thereof in a highly cellular condition.

40 While we prefer to utilize a material such as disclosed the present invention contemplates the use of any insulating material having similar characteristics.

45 One of the essentials in the use of a material such as disclosed, in order to give requisite strength and fire-proofing, is a suitable reinforcement such as is commonly provided in monolithic walls. To provide such reinforcement we utilize three elements; 50 first, a wire fabric of suitable mesh, adapted to be directly laid on to the rafters or structural elements; second, a fabric cover which may consist of tar paper or similar inexpensive paper having the characteristics

of imperviousness to the plastic material to be poured thereon, and third, reinforcing elements laid on the paper above the rafters. Preferably the three elements are so constructed that they may each be handled in rolls and laid out in proper position, the widths being laid side by side to cover the area to be roofed. When the insulating material is poured in position, the reinforcement will be imbedded in the body thereof.

55 The invention will be more readily understood by reference to the accompanying drawings, in which,

Fig. 1 is a sectional view through a roof constructed in accordance with our invention.

70 Fig. 2 is an enlarged sectional view taken on the line 2—2 of Fig. 1, and

Fig. 3 is a plan view, some of the elements being broken away to show the fabric.

75 In the drawings, the structural elements or rafters are indicated at 10. On the rafters is first placed a wire fabric 11. Preferably the fabric consists of ordinary one inch mesh chicken wire which has some resiliency. A fabric cover 12 is provided which may consist of tar paper or building paper.

80 Both the paper and fabric are laid on the rafters and may be secured thereto at intervals if desired. However, the intention is 85 that they shall be permitted to sag under the weight of the cellular material to be poured thereon in order that the said cellular material may underlie the reinforcement which is indicated in the drawings as composed of so-called wire lath. It consists of the narrow mesh fabric 14, and the channels 15, secured thereto. This reinforcement of the form described or of any other suitable form is laid directly on the top of the 90 impervious paper and need be only lightly secured, if at all, to the rafters. Thereafter the body of cellular material, indicated at 16, is poured in place. This material passes through the openings in the reinforcement and its weight exerted on the paper and underlying fabric causes the same to sag, as best shown in Fig. 2, and therefore to imbed and fully protect the reinforcement 95 against fire.

100 If desired, a weatherproof covering 17 is provided. After the pouring of the cellular material and before the setting and harden-

ing are complete, we prefer to level the top surface of the material by screeding or troweling in order to break down the fragile cells at the top surface and provide a dense skin 5 composed of non-cellular gypsum. This expedient, however, is not claimed herein, since it forms a part of the subject-matter disclosed and claimed in Ashenhurst's applications Serial No. 736,892, filed September 10, 10 1924 and Serial No. 12,883, filed March 3, 1925. This surface material sets and hardens quickly and within a few minutes will bear the weight of a workman. This enables 15 rapid completion of adjacent sections of a roof.

Where wood rafters are employed, the same efficiency as to insulation will be secured without complete fire-proofing, relative to an interior fire. However, full 20 protection from outsides fires is assured.

The method here disclosed provides for economical installation of reinforcing or fire-proofing material with reinforcement within the body of the mass, or without the use 25 of forms and the consequent cost in lumber and labor.

A desirable point in the economical installation here described is that the materials used be adapted to be handled in rolls so 30 that they may be laid out on the roof with overlapped edges and temporarily secured thereto in position to receive the plastic material. In Fig. 2, we have illustrated the reinforcing material 14, 15, of a width sufficient to extend between two rafters, the 35 channel strips extending transversely. Inasmuch as the strips 15, and the wires composing the mesh 14, are all soldered or welded together, the material constitutes a rela-

tively strong and rigid reinforcement which 40 may nevertheless be provided in rolls.

The result sought is that of providing insulating and fire-proofing material beneath the reinforcement by utilizing an impervious flexible material adapted to take the place 45 of a form and which will sag under the weight of the material that passes through the reinforcement. This result may be secured in a number of different ways, and we wish it understood, therefore, that we 50 are not to be limited except as indicated in the appended claim.

We claim:

The method of completing a roof between the supporting beams therefor, which comprises stretching a flexible supporting net loosely over said supporting beams, applying a flexible fabric over said supporting net in contact therewith, applying over the fabric a comparatively stronger and stiffer 60 reticulated member, and then pouring into position on said supporting structure a plastic mass adapted to pass through the openings in said second named reticulated member and to press the more flexible supporting members downwardly between the beams into spaced relation with respect to said second named reticulated member for causing 65 said members to be held rigidly in position with the second named reticulated member imbedded in the body of plastic material when such plastic material hardens and sets.

Signed at Toronto, Ontario, Canada, this 24th day of February, A. D. 1925.
